JOHN PINTER, OF ST. LOUIS, MISSOURI.

Letters Patent No. 89,166, dated April 20, 1869.

IMPROVED WASHING AND WRINGING-MACHINE.

The Schedule referred to in these Letters Patent and making part of the same.

To all whom it may concern:

Be it known that I, JOHN PINTER, of St. Louis, in the county of St. Louis, and State of Missouri, have made certain new and useful Improvements in Washing and Wringing-Machine; and I do hereby declare that the following is a full and clear description thereof, reference being had to the accompanying drawings, and to the letters of reference marked thereon.

The nature of this invention is in the peculiar construction and arrangement of the devices for giving a longitudinal vibration to the washing-rollers, and in the specific arrangement of the apron, conveyer, compressor, and wringer-devices, all of which hereinafter more fully appears.

To enable those skilled herein to make and use my said invention, I will now fully describe the same, referring to the accompanying—

Figure 1, as a plan of my said improved machine;

Figure 2, as a side elevation;

Figure 3, a central longitudinal sectional elevation; and

Figures 4 and 5 are detail figures, hereinafter more fully referred to and described.

I construct the operating-devices of my said machine to be supported in proper frame-work A, usually of wood or cast-iron, the same being placed within a closed tub, or vessel, A', arranged to hold water or other washing-fluid.

The fluid in the tub A' will usually stand to the level indicated by the line x y of fig. 3, so that the stuffs to be washed may be properly immersed.

Said stuffs will be fed to the washing and scrubbing-rollers through a feed-slot, a, in the end of the vessel A', upon the feed-board a'.

From this feed-board, said stuffs pass to the rollers B B', to be thoroughly scrubbed and washed, as now to be described.

Of said rollers B B', the lower one, B, will be supported by its journals, b, directly in the frame A by proper bearings.

One of said journals will extend out to receive the gear-wheel C, which, by other wheels, is connected with the driving, or power-shaft, and is thereby turned, thus turning said roller B. On said roller B, and in engagement therewith, rests the roller B'.

Both of said rollers B B' are formed of series of corrugated slats b¹, well fastened, by bands or similar means, to a central shaft or body. Said slats form spurs, or radial projections, and the rollers overlie each other, so that the spur-slats thereof engage upon each other similar to the teeth of ordinary gear-wheels.

The slats b¹ are formed with segmental or rounded surfaces, as indicated, in transverse section, in fig. 3, and the segmental surfaces moreover, have corrugations b² running longitudinally along the slats, as indicated in plan, fig. 1.

By the engagement of the rollers, as aforesaid, the roller B, in revolving, also turns the roller B', and stuff

fed between them is drawn through, being compressed and scrubbed in its passage. In order that said scrubbing-action may be the more perfect, I arrange the roller B' for a lateral reciprocating motion in the manner following:

By connection from the main power-shaft, I rotate the gear-wheel C' on the shaft c.

Said shaft carries, at its end, the drum c'.

On said wheel C' is the pin d, operating the connecting-rod d'.

This operates the pin d', hinged, by the forked lever d', to the rock-shaft d', said shaft having journal-bearings in the frame A.

On said shaft d', I secure the tappet d⁵.

In exact counterparts, I arrange, in connection with the drum c', and operated by the same, the pin e, connecting-rod e', pin e'', forked lever e'', and rock-shaft e'', and tappet e⁵, the same being on the other side of the main frame A. All said parts are more plainly shown in detail, fig. 5, in plan.

In order that said parts may operate the roller B', I arrange, at the ends thereof, the sleeve f, through which the bolt f¹ passes, so that the roller B' and its sleeve may freely turn thereon.

At the rear of said bolt f¹, a nut, f⁶, prevents lateral disengagement, and, at the forward end, the bolt f¹ connects, by a hinge-joint, with hinged lever f², hinged at f³, and pivoted in the main frame A at f⁴.

At its forward end, said lever f² has the tappet-end f⁵. Therefore, in the pendulous motion of the tappets d⁵ and e⁵, before referred to, the tappets f⁵ will be moved laterally, thus also imparting the desired reciprocal motion to the roller B', as heretofore stated.

By the hinged connection of the lever f² with the main frame A at f⁴, the roller B' may rise vertically, or radially, off from the lower roller, B, and thus a great or small quantity of cloth or stuff may be fed between said rollers.

Under the said washing-rollers, and slightly beyond the same, I arrange the carrying-belt G, passing around the rollers g and f², which are journalled in the frame A. Said belt, being continuous, is driven as an ordinary power-belt by the roller g, the journal whereof extends beyond the frame A, and has the gear-wheel D in proper engagement with such intermediate wheels as secure a transmission of power and motion from the main power-source.

Over said belt, I arrange the conveyer H, the same being formed of a chain, with straight links h, hinged together.

Alternate links extend out so as to include between them the hasps h¹ on the driving-roller H¹.

The journal hereof extends beyond the frame A, and has a gear-wheel, E, for transmission of power from the power-source.

At the lower end of said conveyer, a roller, H², limits the traverse of said conveyer, as indicated in fig. 3.

On the longer links, h, I arrange, by proper standard-

supports, the rollers h^2 , turning freely on their journals in said standards.

By the arrangement of said conveyer and its rollers above the belt G , the clothes, as they are carried upon the belt, are compressed and scoured by said rollers, besides being held to such contact with the running belt as will insure the upward transmission.

In order, however, that the belt G may not slacken, and to make the pressure of the rollers of the conveyer more effective, I arrange the compressor roller frame I , carrying rollers i , which turn freely on their journals.

Said frame I has a slotted guide, i^1 , in which a proper set-screw, i^2 , secures the frame I to the main frame A .

The springs i^3 rest against the under edges of the frame I , and abut centrally against the block i^4 on the frame A . Thus the roller-frame I and its rollers i are pressed against the belt G , and proper pressure is insured against the cloth as it passes. By adjusting the frame I by its guide i^1 , the pressure thus given may be regulated.

It is plain that the conveyer-rollers h^2 on the one side, and the rollers i on the lower side, act not only to scrub and cleanse, but also to wring out moisture from the cloths as they pass up, and thus prepare the same for receival at the wringer K .

Said wringer has two rubber or similar elastic rollers, K^1 K^2 , the lower one, K^2 , being arranged for operating the belt G . Said rollers have their journals secured in bearings in the main frame A , and power is transmitted from the one journal to the other by gear-wheels, in the ordinary manner.

In order that the upper roller, K^1 , may be forced down with proper pressure upon the lower one, I arrange the compressors k . These are usually strong

wooden or metallic springs, secured to the frame A at the point k^1 , and arranged to be drawn down by hasps or sliding clasps, k^2 , which move longitudinally in proper slots of the main frame, and which, when forced back, draw down the compressors k (as seen in fig. 3) upon the journals of said roller K^1 .

Power is supplied from a main shaft, L , and transmitted to the various devices hereof by gear wheels, belt, and shafts, in the manner usual, and generally as indicated in the several figures.

When the said machine is used for simply drenching clothes, in "bluing" or "starching" or in "dyeing," and similar operations, then the washing-rollers B are not specially needed in their operative action. In this case, proper lifters may be arranged to elevate the hinged levers f^2 or the roller B' itself, so that said roller will not be in engagement with the propelling-roller B , and so that the tappets d^3 e^5 shall not act upon the tappets f^2 .

Having thus fully described my invention, What I claim, is—

1. The shaft c , wheel c^1 , and parts d^1 , d^2 , d^3 , d^4 , and d^5 , combined and arranged with the parts f^3 , f^2 , f^1 , and f and the roller B , substantially as and for the purposes set forth.

2. The arrangement of the belt G , conveyer H , compressor I , and wringer K , substantially as and for the purposes set forth.

In witness whereof, I have hereunto set my hand, in the presence of—

JOHN PINTER.
